CLAIM

The ornamental design for a coil for substrate mounting as shown.

DESCRIPTION

FIG. 1 is a perspective view of a coil for substrate mounting showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is an exploded perspective view thereof.

The broken lines illustrate portions of the coil for substrate mounting that form no part of the claimed design.

1 Claim, 9 Drawing Sheets
